TIME RECORDING DEVICE

Georges Pagnard, Moutier, Switzerland, assignor to Omega, Louis Brandt & Frère S. A., Bern, Switzerland

Application January 18, 1956, Serial No. 560,028

Claims priority, application Switzerland February 23, 1955

5 Claims. (Cl. 346—141)

The present invention relates to a time-keeping apparatus and more particularly to a time-recording device in which indications of lengths of timed intervals are printed.

The time recording device in accordance with the invention is of the known type such as is disclosed in my co-pending application Serial No. 257,250, filed November 20, 1951, which has matured to Patent No. 2,757,063, issued July 31, 1956. This application shows a recording device in which the length of the timed interval is recorded on a chart which is advanced on each recording operation, the imprint on the chart being made by a quick-acting striker operative on the inertia principle, the imprint being made so quickly that no appreciable blurring occurs at an accuracy of one thousandth of a second.

The striker disclosed in the above-mentioned application is formed of a mass of metal attached to an armature by means of springs. The striker is arranged above the timing means which include drums of a counter, an inking ribbon being inserted between the striker and a paper strip adapted to record the timed intervals. When a current impulse energizes the coils controlling the armature, the latter is suddenly attracted and drags along the striker. When the armature is stopped against its coils, the spring-supported striker, by its inertia, in a snapping action impacts the ribbon against the counter drums to imprint the timed interval upon the paper strip. The armature is then brought back into its rest position under the action of a restoring spring.

The impression thus obtained on the paper strip is not always wholly satisfactory. In some cases the figures are almost illegible owing to the fact that the counter drums are not perfectly aligned.

The present invention aims to overcome this difficulty. In the time recording device in accordance with the invention, the striker is made with a plurality of hammers controlled by a common member, each hammer corresponding to one of the counter drums, means being provided for individually adjusting the striking force of each hammer.

The accompanying drawing shows schematically, by way of example, an embodiment of the invention.

Fig. 1 is a plan view of a portion of the recording device of a construction in accordance with the invention.

Fig. 2 is an elevation view taken from the left of Fig. 1.

Fig. 3 is an elevation cross-sectional view of the striker mechanism.

There is shown in the drawing only sufficient structure for an understanding of the invention, other details may be seen in my co-pending patent application Serial No. 257,250, the present invention disclosing in part, an improvement over the structure described and illustrated in said co-pending application.

Referring to the drawing, the time recording device includes a mechanical counter having drums 1 carrying relief numerals. The drums 1 may be driven by a syn-

2

chronous motor which in turn may be fed by a quartz clock (not shown). Above the drums 1 is guided a paper strip 2 adapted to receive the impression of the relief numerals carried by the drums 1. Above the paper strip 2 is arranged an inking ribbon 3 or a carbon-paper strip which is fed from a supply roller 4.

The impression on the paper strip 2 is produced by means of a striker mechanism including four coils 5, a common armature 6 which is attracted by a current impulse arriving in the recording device at the precise instant of a time to be recorded. The armature 6 is formed of two superposed plates 6a and 6b assembled by means of screws 7. The lower plate 6b, which is adapted to come into contact with cores 8 of the coils 5, is broken off in the region of the drums 1. The armature 6 is rigidly fixed to a rotary shaft 9 pivoted in frame 10 of the recording device by means of ball bearings 11. The armature 6 has an extension providing two lugs 12 each of which has attached one end of a restoring spring 13, the other end of which is attached to the frame 10.

The striker mechanism includes a plurality of hammers 14 each corresponding to one of the counter drums 1. The hammers 14 are freely mounted on a shaft 15 supported by two bosses 16 carried by the armature 6.

Each hammer 14 has in its central portion a tapped hole 17 into which is screwed a headless screw 18. A pin 19 extending upwardly from the armature 6 serves for guiding a small coil spring 20 bearing at one end against the armature 6 and bearing at its other end against the inner face of the screw 18. The pin 19 is made with a length such that, in the rest position of the hammers 14, i. e. when no current passes through the coils 5, the pin 19 is only partially engaged in the hole 17, and a predetermined clearance remains between the free end of the pin 19 and the screw 18.

Each hammer 14 has at its free end a fork-shaped portion 21 between the prongs of which is fixed, by means of rivets 22, a mass 23 having a high specific weight, for instance, made of a tungsten alloy.

When a current impulse arrives in the coils 5, the armature 6 is suddenly attracted and drags along in its movement the shaft 15 and the hammers 14. When the armature 6 stops against the cores 8 of the coils 5, the hammers 14, by their inertia, continue their travel and compress the springs 20 and print the relief of the counter drums 1 onto the paper strip 2. The hammers 14 are snapped back under the action of the springs 20. Simultaneously, under the action of the restoring springs 13, the armature 6 is brought back into its rest position, its movement being limited by a stop screw 24 carried by the frame 10.

By turning the screws 18 of the several hammers 14, it is possible to adjust exactly the striking force of each hammer so as to compensate for a possible inaccurate alignment of the counter drums 1. It is thus possible to obtain an absolutely uniform impression of the several figures on the paper strip 2.

The striking operation is extremely rapid, so that the slight braking produced by the hammers 14 on the counter drums 1 does not effect the measurements by an error greater than the required precision. The device as shown and described permits recording timed intervals with a precision of one one-hundredth of a second.

While I have described and illustrated one embodiment of my invention, I do not wish to unnecessarily limit the scope thereof, but reserve the right to make such modifications and rearrangements of the several parts as may come within the purview of the accompanying claims.

What I claim is:

1. In a time recording device of the type comprising

a plurality of timing means, starting means for the timing means, recording means, striker means to impact the recording means against the timing means in marking relationship, spring means carrying the striker and normally maintaining the striker in non-marking position, striker operating means to set the striker in motion, the striker, by its inertia, adapted to impact the recording means against the timing means in marking contact, and adjustment means for the starting of the timing means correcting for the inherent striker lag, the improvement wherein the striker includes a plurality of hammers, a common member for the control of the plurality of hammers, each hammer corresponding to one of the timing means, and means for individually adjusting the striking force of each hammer.

2. A time recording device according to claim 1, in which the common member controlling the hammers is an armature cooperating with at least one electromagnet.

3. A time recording device according to claim 2, in

which a shaft is included carried by the armature and the hammers are freely mounted on the shaft.

4. A time recording device according to claim 2, in which each hammer has a tapped hole receiving an adjusting screw, and a pin fixed to the said armature serves for guiding a coil spring bearing against the armature and the screw.

5. A time recording device according to claim 1, in which each hammer has at its free end a fork-shaped portion and a mass having a high specific weight is positioned between the prongs of the fork-shaped portion.
